TOY SUBMARINE

Alexander J. Middler, Detroit, Mich.

Application January 20, 1939, Serial No. 251,897

11 Claims. (Cl. 46—94)

This invention relates to toy submarines and has for its object to provide a toy of attractive appearance which will dive intermittently over a period of minutes and, preferably, which will then cruise on the surface of the water until removed.

The principal object is to provide means for controlling the diving function which is operable when the submarine is at a depth which may be predetermined for causing the submarine to return to the surface of the water, and to teach alternative means for obtaining such control. For example, in the case of a toy submarine of buoyant nature having diving fins and propelling means causing it to dive incident to forward movement through the water, the speed of forward movement is the controlling factor. The present invention is applicable to reduce the speed of forward movement to such an extent that the buoyancy of the submarine returns it to the surface of the water. In the case of a submarine having means for varying its buoyancy to cause it to intermittently dive and rise to the surface, the invention is applicable to control the buoyancy.

Another object is to provide a toy submarine having diving fins and propelling means, and means which functions to reduce the speed of operation of the propelling means when the submarine is diving at an angle which may be predetermined or, alternatively, means which functions in the presence of water pressure which may be predetermined for reducing the speed of operation of the propelling means, in order that the buoyancy of the submarine will return it to the surface.

Another object is to provide a toy submarine having buoyancy chambers and a compressed air storage tank, and means for controlling the supply of compressed air to the storage chambers to supply air thereto when the submarine is diving at an angle which may be predetermined.

Other objects and advantages will become more fully apparent as reference is had to the accompanying drawing wherein my invention is illustrated and in which:

Fig. 1 is a side elevation of a toy submarine,

Fig. 2 is a fragmental vertical cross section with the mechanism in diving trim,

Fig. 3 is a view similar to Fig. 2, with the mechanism in a position permitting the submarine to rise,

Fig. 4 is an elevation of a braking member,

Fig. 5 is a view similar to Fig. 2 illustrating water pressure actuated braking means, and

Fig. 6 is a longitudinal section of a submarine having means for varying the buoyancy thereof and a control which is actuated when the submarine dives at a predetermined angle.

Referring to Figs. 1 to 4, a toy submarine

hull 1 having fins 2 disposed at an angle which cause the hull to submerge when moved forwardly through the water at a certain speed. The means for propelling the hull comprises a propeller 3 mounted on a shaft 4 and driven through gearing 5 by a spring motor 6. The gearing and spring motor are such that they ordinarily propel the hull at a rate causing the diving function.

10 Upon the shaft 4 are two fixed collars 7 and 8 and a disc 9 is pressed against the collar 8 by a spring 10 which bears against the collar 7. The disc 9 ordinarily rotates with the shaft 4, and as may be seen more clearly in Fig. 4 has a radially projecting prong 11.

Pivotedly mounted in a fixed bracket 12 is a bell crank lever having a weight 13 on its upwardly extending arm 14, and its lower arm 15 in loose engagement with a latch 16 which is

20 adapted to engage the prong 11 to prevent rotation of the disc 9. An eccentric disc 17 mounted on a hand operated stem 18 restricts pivotal movement of the weight 13, and by movement rotatively may cause the arm 14 to be held in

25 different angular positions. With the hull disposed horizontally, the weight 13 ordinarily rests against the eccentric 17, and when the hull assumes an angular position corresponding to the diving angle the weight and arm 14 fall forward-

30 and cause the latch 16 to rise and engage the prong 11 to stop rotation of the disc 9. Friction between the disc 9 and collar 8 brakes the propeller shaft and slows forward movement of the hull to such an extent that buoyancy of the

35 hull tends to return it to the surface.

In order to maintain the braking action until the hull reaches the surface a latch mechanism is provided to hold the weight 13 in its forward position. This latch mechanism comprises

40 a float 19 pivoted at 20 and connected to a finger 21 for moving the latter into engagement with the weight 13. After the hull is completely submerged the float 19 rises and pivots the finger 21 into a position where it will engage

45 the weight when the weight is in its forward position to retain it in its forward position. The finger 21 remains in contact with the weight until the hull rises to the surface, at which time the float descends from the position shown in Fig. 3,

50 thereby releasing the weight and allowing it to fall back to the position shown in Fig. 2 and to withdraw the latch from the prong 11. The cycle is repeated until such time as the power stored in the spring motor is completely expended.

It will be noted upon reference to Figs. 2 and 3 that the bell crank arm 15 and the latch 16 are correlated to provide for a lost motion action therebetween. The result of this arrangement is that upon release of the weight 13 the bell crank

rocks freely a short distance so that the arm 15 forcibly strikes the latch 16 and withdraws it from engagement with the prong 11.

The braking action induced by the spring 10 preferably is sufficient to completely stop rotation of the propeller shaft 4. Therefore, when the spring motor is being wound it is not necessary to manually hold the propeller stationary. By lowering the bow and elevating the stern the weight 13 falls forward to the brake actuating position and holds the brake applied, and permits the motor to be wound and the submarine to be carried from place to place while wound.

Obviously, the normal angle between the arm 14 and the vertical determines the angle at which the weight falls forwardly. This normal angle may be varied by rotating the eccentric disc 17.

In Fig. 5 there is illustrated a fragment of a hull 1a similar to that above described and having a propeller 3a on the drive shaft 4a which is adapted to be driven in the manner above described. Mounted in the hull 1a is a housing 25 having a diagram 26 adapted to deflect in response to water pressure. When the diaphragm 26 deflects a brake shoe 27 is moved into contact with the shaft 4a and reduces the speed of rotation thereof.

In Fig. 6 there is illustrated a hull 30 having a compressed air tank 31 and a buoyancy chamber 32 therein, the hull being ported at 33 in order that air or water may enter and leave the same. The buoyancy chamber has a port 34 opening through the bottom of the hull and a port 35 opening into the interior of the hull. Extending from the tank 31 is a conduit 36 having a port 37 opening into the chamber 32.

A double valve 38 is operated by a weighted lever to control the ports 35 and 37, the weighted arm when positioned as shown in full lines causing the valve 38 to close the port 37 and to open the port 35. Therefore water may enter the port 34 and displace air through the port 35 from the chamber 32. The tank 31 is mounted toward the rear of the hull and the forward end therefore sinks more rapidly than the rear end, and as a predetermined angle is reached the weighted arm 39 falls forwardly to the dotted line position shown. The valve 38 closes the port 35 and opens the port 37, thereby admitting compressed air to the buoyancy chamber 32 to displace water therefrom, at which time the hull rises to the surface and repeats the cycle.

Although a specific embodiment of the invention is illustrated and described, it will be understood that various changes may be made within the scope of the appended claims without departing from the spirit of the invention, and such changes are contemplated.

What is claimed is:

1. In combination, a toy submarine hull, means for causing said hull to dive, and means automatically operated as a result of the diving function for causing said hull to return to the surface, said last named means including a control member adapted to be moved by gravity when the hull becomes angularly disposed as a result of diving.

2. In combination, a toy submarine hull, fins on said hull for causing said hull to submerge incident to a predetermined speed of movement, a

motor for propelling said hull at or above said speed, and means for reducing the speed of said motor.

3. In combination, a toy submarine hull, fins on said hull for causing said hull to submerge incident to a predetermined speed of movement, a motor for propelling said hull at or above said speed, and means operated by angular disposition of the hull as a result of diving for causing said hull to return to the surface.

4. In combination, a toy submarine hull, fins on said hull for causing said hull to submerge incident to a predetermined speed of movement, a motor for propelling said hull at or above said speed, and means operated by angular disposition of the hull as a result of diving for reducing the speed of said motor below said predetermined speed.

5. In combination, a toy submarine hull, means for causing said hull to dive, means operated by angular disposition of the hull as a result of diving for causing said hull to return to the surface and means for adjusting said last named means to vary the angle at which it operates.

6. In combination, a toy submarine hull, fins on said hull for causing said hull to submerge incident to a predetermined speed of movement, a propeller, a spring motor for driving said propeller, and a brake adapted to operate intermittently during the operation of said motor for reducing the speed of rotation of said propeller.

7. In combination, a toy submarine hull, fins on said hull for causing said hull to submerge incident to a predetermined speed of movement, a motor for propelling said hull at or above said speed, a weight pivotally mounted to swing in response to inclination of said hull, and a brake for said motor operated by swinging movement of said weight.

8. In combination, a toy submarine hull, fins on said hull for causing said hull to submerge incident to a predetermined speed of movement, a motor for propelling said hull at or above said speed, a weight pivotally mounted to swing in response to inclination of said hull, a brake for said motor operated by swinging movement of said weight, and a float member for holding said brake applied after initial application thereof and until the hull reaches the surface of the water.

9. In combination, a toy submarine hull, means in said hull for causing said hull to sink, and means operated by angular disposition of said hull as a result of diving for operating said first named means to cause the hull to rise to the surface.

10. In combination, a toy submarine hull, a compressed air storage tank, a buoyancy chamber, and means operated by angular disposition of said hull as a result of diving for controlling the passage of air from said tank to said chamber.

11. In combination, a toy submarine hull, a compressed air storage tank, a buoyancy chamber, means operated by angular disposition of said hull as a result of diving for controlling the passage of air from said tank to said chamber, and means for retaining air in said buoyancy chamber when the supply of compressed air is depleted to a predetermined extent.
